[57] CLAIM

The ornamental design for a battery-operated light, as shown and described.

DESCRIPTION

FIG. 1 is a perspective view of one embodiment of the battery-operated light according to the invention; FIGS. 2, 3 and 4 are top plan, side elevational, and bottom plan views, respectively, of the embodiment of FIG. 1;

FIGS. 5 and 6 are front and rear elevational views, respectively, of the embodiment of FIGS. 1 to 4;

FIG. 7 is a perspective view of another embodiment of the battery-operated lights;

FIGS. 8, 9 and 10 are top plan, side elevational and bottom plan views, respectively, of the embodiment of FIG. 7; and

FIGS. 11 and 12 are front and rear elevational views, respectively, of the embodiment of FIGS. 7 to 10.
